SYDNEY B. CARNE, OF SAN FRANCISCO, CALIFORNIA

BAND-PLAYER'S MUSIC RACK

Application filed November 10, 1928. Serial No. 318,414.

This invention relates to music holders for band players and has for its objects a device for wearing by a marching musician which will effectively hold the music for him to read, and which will be adjustable to every position, and which will be unaffected by the necessary arm movements in playing some instruments, or in marching along the streets.

Briefly described the invention comprises a light frame of wire or tubing or similar construction formed and arranged to lie against the body of the musician under one arm, and which frame is strapped to the body by means of a strap passing around the shoulder and neck of the wearer. This frame provides a rigid base as it were for an arrangement of adjustable arms, and at the outer end of the arms is supported a music rack which clamps the music in position for reading by the musician.

In the drawings accompanying this application Fig. 1 is a perspective view of a musician with my improved music holder strapped in place and a sheet of music in position.

Fig. 2 is an enlarged view in perspective of the adjustable joints directly beneath the music holder.

Fig. 3 is an enlarged view of the adjustable joint of the device adjacent the body of the wearer, and Fig. 4 is an enlarged end view of the adjustable joints at the lower part of the body frame and showing two rods passing therethrough in sections.

Figs. 5 and 6 are respectively enlarged plan and vertical cross section of an optional adjustment joint which may be used in place of that shown in Figs. 3 and 4.

In the drawings at 1 is shown a standing or walking musician and positioned against his left breast and passing under the left arm is a kidney-shaped wire or tubular frame 2. This frame is curved to lie against the body, and the upper run of the frame is bent downward in the form of a loop as at 2' so as to fit under the arm, while at the extreme ends of the frame are small wire loops 3 to which is attached a strap 4 passing around the neck and shoulder of the wearer and adjustably buckled at 5 so as to hold the

frame 2 snugly against the left side of the body of the wearer in the manner shown.

At the lower portion of the kidney-shaped frame the wire is formed with a short horizontal run as at 2'' and fitted thereover is a split clamp 6. Split clamp 6 is formed as shown clearly in Fig. 4 where it will be seen to comprise two similar portions which may be tightly clamped together by means of a thumb screw 7 passing freely through one member and threaded into the other member as shown, and the clamp members are formed with oppositely disposed recesses adapted to embrace a pair of parallel rods. In Fig. 1 the upper recess of the clamp embraces the straight run 2'' of the frame 2, and the lower recess embraces rod 8 extending across the chest of the musician, and fitted at the end of rod 8 is an adjustable joint 9 clamped by means of a thumb screw 10 and from which adjustable joint extends a rod 11 carrying at its outer end a joint or clamping member 12 adapted for clamping to the rod 11 at various positions therealong, and also adapted for clamping to a vertical rod 13.

The joint device 12 is best shown in Fig. 2 where it will be seen to comprise oppositely projecting split portions respectively engaging the rods 11 and 12 and independently clamped thereto by the set screws or thumb screws 14 and 15 in a manner permitting either rod to slide through the joints or either rod to turn upon the joints or in the joints when its respective thumb screw is released.

At the upper end of rod 13 is a conventional music holder or spring clamp taking the form of a lyre 16 and in which the sheet or book of music 17 is held.

By the arrangement shown the lyre supporting rod 13 may be adjusted up and down or turned about when screw 15 is released, or it may be swung bodily in an arc from rod 11 when screw 14 is released, or slid bodily along rod 11 to any desired position, or rods 11 and 13 may be swung as a unit about the vertical pivot formed by the joint 9, or the three rods 8, 11 and 13 may be bodily slid in and out in the clamp 6, or bodily rocked in clamp 6 on the axis of rod 8. Thus any desired position of adjustment, elevation or an-

gular relation of the music to the eye of the musician may be readily obtained with simple and easily adjustable parts, all carried on a relatively rigid frame 2 strapped firmly to the body and which is unaffected by the ordinary arm and leg movements of the musician in marching along the streets, or the movements of his instrument in playing.

In place of the slideable clamp joints 6 which hold rods 8 and 2" in the desired relation, the rods may be simply welded or otherwise permanently connected together at the point of clamp 6, and the joint shown in Figs. 5 and 6 substituted for the joint 9. Joint 15 shown in Figs. 5 and 6 comprises a pair of clamping plates 18 which may be firmly clamped together by means of a thumb screw 19 to simultaneously grip rods 8 and 11 in the manner shown in the figures. Rod 11 is 20 preferably enlarged slightly at its end as shown at 11' so that it will not easily pull out of the clamping plates 18 when the screw 19 is released, but may be rotated in the clamp to any point desired. This joint permits of 25 sliding the rod 11 bodily along rod 8 instead of sliding rod 8 in the clamp 6 shown in Fig. 1, and in some respects forms a neater joint as it is controlled by a single screw 19 in place of the two screws 7 and 10 required in Fig. 1 30 to effect the same control.

It is evident from the above description that many modifications may be made in the various joints providing adjustability of the music holder, or that the various joints may 25 be entirely dispensed with and a single rigid wire or rod run from the lower part of the frame 2 directly upward to the music holder 16, and which rod may be forcibly bent to any desired position to suit the individual 40 wearer, but any such changes or modifications used in connection with a rigid body frame 2 I feel to come within the spirit of my invention and accordingly the appended claims are drawn to cover any such variations in 45 my device.

I claim:

1. A band player's music holder comprising a kidney-shaped frame formed to fit against the chest and under the arm of the 50 wearer, means adapted for securing the frame in such position, and a music-supporting rack extending from and secured to said frame.

2. In a structure as specified in claim 1, 55 said kidney-shaped frame formed of wire with an upper and a lower run, and the music-supporting rack extending from the lower run.

3. A band player's music holder comprising a kidney-shaped frame formed to fit against the side of the chest and under the arm of the wearer, a strap attached to opposite ends of the frame arranged and adapted 60 for passing around the neck of the wearer for buckling the frame to his body, and a

music-holding rack extending from said frame.

4. In a construction specified in claim 3, 70 said frame made of wire and loops formed at opposite ends thereof to receive the ends of said strap so that the strap and frame will not shift relatively.

5. In a structure as specified in claim 3, 75 said music-holding rack including a bar extending from said frame horizontally in front of the wearer for a distance, and extensions from said bar projecting outwardly and upwardly.

6. In a structure as specified in claim 3, 80 said music-holding rack including a bar extending from said frame horizontally in front of the wearer for a distance, and extensions from said bar projecting outwardly and upwardly, and an adjustable clamping joint at each change of direction of said bar.

7. In a structure as specified in claim 3, 85 said music-holding rack including a bar extending from said frame horizontally in front of the wearer for a distance, and extensions from said bar projecting outwardly and upwardly, and an adjustable clamping joint at each change of direction of said bar, the outer end of the bar being directed vertically, and a music sheet clamp mounted on the upper end of the vertical bar.

SYDNEY B. CARNE.
